SOLENOID ACTUATED INTERRELATED LOCKING MEANS FOR FLOW CONTROLS IN A PLURALITY OF INDEPENDENT CHANNELS

George Donald Hendricks, Campbell's Island, and George Leland Rambo, Moline, Ill., assignors to Eagle Signal Corporation, Moline, Ill., a corporation of Massachusetts

Application August 26, 1954, Serial No. 452,368

1 Claim. (Cl. 200—98)

The invention relates to solenoid actuated interrelated means for locking any one of a number of control devices, each controlling flow through its own channel, either in the position to permit flow, or to prevent flow, through that channel.

The invention is applied to a plurality of channels each carrying a fluid and provided with a valve controlling flow of fluid through the channel, or to a plurality of channels each carrying an electric current and provided with a switch controlling the flow of current through the channel.

The essence of the invention lies in solenoid actuated means that will, upon actuation of the control device of one of a plurality of channels, lock that control device in actuated position and, in so doing, will release any other control device previously locked to allow each of these other control devices to assume its original position.

The invention provides a series of compact relay units, each actuated by its own solenoid, and so designed that upon actuation of a relay the circuits to be closed are closed without rebound of one contact relative to the other, avoiding the sending of an interrupted current that might cause devices to respond several times when only a single response is intended.

Thus, where it is desired that only one channel shall be in operation at a time, one channel may be closed or opened and the act of placing that channel in that condition will take the other channels that have been previously placed in that condition out of that condition.

The channel may be placed in operation by sending a current through a relay. The relay will then actuate the control device in that channel and, in so doing, will lock itself in actuated position and remain in that position even though the current through the relay ceases. Further, in the act of locking itself, the relay will release any other relays in the group that have been previously locked.

One of the advantages offered by the use of such interrelated control latching means is that the current on a relay need not be maintained after the relay is latched. If the current had to be maintained on a relay to hold it in activated position heat would be generated which would have serious drawbacks where the relays are in a closed compartment and the current may flow through the relays for hours at a time.

A distinctive feature of the present invention is that the circuit that is closed is closed with less chance of bouncing of the movable contact engaged in the closure relative to the fixed contact, than in existing interlocked relays. Any sensitive device in the circuit, responsive to each current flow, will not erroneously be caused to respond more than once to a single actuation of the relay.

The invention is illustrated by channels whose control devices are mechanically interrelated.

In a modified form of the invention all the channels in a group function except one channel, and upon actuation of a relay connected to another channel, that other channel will become inactive and the act of latching that channel in the inactive position will cause all other channels that are not already closed to function.

2

The invention may be applied to transmission systems feeding power or signals over a single channel that branches off into a number of channels each leading to a different power actuated device by placing a control device in each of these channels and closing the circuit to one of the relays to establish a circuit through one channel. The current to the relay need only flow long enough to lock that relay and open the relays on the other channels so that only one of the devices receives current.

The mechanical device that unlocks the other controls or switches is very much simpler than electric circuits to achieve the same result. Such circuits are shown in Figure 6 in an application entitled Replacement of a Plurality of Channels by a Single Channel, filed on September 2, 1953, by Donald Hendricks et al. and bearing Serial Number 378,057.

While interrelated relays have been known, the invention provides a more compact and novel apparatus for accomplishing the desired end than has been hitherto available.

The object of the invention is to provide simple means whereby the locking of the control in one of a plurality of channels will unlock the controls in the other channels without requiring continuous current through a relay.

A further object of the invention is to actuate the switch in one of a plurality of electrical circuits, the act of actuating the switch locking it in its actuated position and automatically releasing any of the switches in the other circuits that were previously locked.

A further object of the invention is to provide mechanical interlocking means for a plurality of relays, each relay so designed as to reduce the weight of the armature and its range of motion to minimize the tendency of the closure of that circuit to be subject to interruption by vibration.

Figure 1 is a plan view of a portion of a unit showing four circuits which illustrates the invention.

Figure 2 is a vertical section taken along lines 2—2 in Figure 1 showing a circuit latched.

Figure 3 is a partial vertical section taken along lines 3—3 in Figure 1 drawn to a larger scale.

Figure 4 is a rear elevation of one of the units.

Figure 5 is an elevation, similar to Figure 2, showing a modification.

The invention will be illustrated by describing an electrically actuated group of switches in a plurality of channels.

There may be any number of solenoid actuated units; four units A, B, C, D are shown by way of illustration. As the units are duplicates of each other, only unit A will be described in detail.

A base 1, supported on pads 2, carries units A, B, C, D. The base 1 may be a metal stamping having portions 3 at each end that are bent upward to form posts. At least one of these posts 3 has a horizontal extension 4. A rod 5 passes through holes in each of these posts.

A pawl-plate 6 has upturned ends 7, each end being pierced to allow rod 5 to pass through these ends. Thus the plate acts as pawl, see Figure 3, that swing about rod 5. A coil spring 8, under light tension, has its ends attached to the pawl-plate 6 and the extension 4 to bias the pawl 6 to turn clockwise in Figure 3. The pawl may have an extension 9 to permit manual movement of the pawl.

The solenoid actuated units are designed to be compact, light in weight to facilitate prompt movement of the parts, with contacts so arranged that once a circuit is closed or broken, there will be no blurring by vibrating or bouncing contacts.

Each of the units A, B, C, D has a plate 10 attached to the base which has a vertical section 11. Supported on this plate is a U-shaped stamping 12 having vertical legs 13, 14. The stamping 12 may have an orientation hole into which the end of plate 10 fits as shown in section in Figure 2. Leg 14 extends upward and carries a horizontal pivot 16. This U-shaped piece 12 also supports a solenoid 19. An armature 17 for this solenoid, has ears 18 that pivot at 16. The armature has a rearward extension 21. A tension spring 22 has its ends connected respectively to this extension and to the lower part of leg 14. This spring tends to lift the right hand end of the armature, as seen in Figure 2.

To limit the upward motion of the armature, it is provided with a hole through which the bent stop 23, attached to leg 13 of the U-shaped piece, extends.

The armature 17 also carries a slot 24 through which the latch bar 25 extends. The lower end of the latch bar is guided by hole 27 in base 1. The upper end of the latch bar carries a finger 26 that rests on the armature so that, as the armature is elevated by spring 22, the latch bar too will be elevated. The latch bar has a notch 28, and a recess 29 separated by a rise 30. The pawl 6 is adapted to rest either in notch 28 or in recess 29 but is rocked by the rise 30 as the latch bar moves downward so that the pawl that was in recess 29 will bear against notch 28.

An insulating plate 35 is attached to vertical leg 11 of plate 10.

This plate, as shown in Figure 1, carries two terminals 33, 34 that are connected to lines 31, 32 leading to solenoid 19.

The insulating plate also carries a stamping 36 having terminal 37 and a contact 38.

The armature 17 carries an insulating plate 40 on which the switch arm 41 is mounted. The switch arm carries contact 42.

It will be obvious that if the holes 27 in the base 1 are stamped along a line, and the plates 10 attached to the base in such alignment that each upturned end of the plate will place the orientation hole of each stamping 12 in the same position relative to one of the holes 27, the several units A, B, C, D may be duplicates.

The stamping 12 places the pivot 16 close to the solenoid 19, providing a short, light, armature 17.

The electrical circuit is closed or opened by a single contact 42 carried by switch arm 41 which engages either contacts 38 or 44.

Since the distance of contact 42 from the pivot 16 is comparable to the distance the solenoid axis is from the pivot, only a small rocking movement of the armature is needed which cuts the effect of inertia.

In a modified form the insulating plate 35 also carries an additional bent plate 43 having a terminal 45 and a contact 44.

A terminal 46 carried by plate 35 is connected by a cable 47 to switch arm 41.

When the device is installed, each circuit is connected with terminals 37 and 46 in one of the units A, B, C, D. To complete the circuit, the armature must be in its latched position with pawl 6 lying against notch 28.

Each of the solenoids 19 is connected through its terminals 33, 34 with a circuit that is energized when that circuit which is connected to that pair of terminals is to be connected up and the other circuits interrupted.

After the various terminals have thus been connected up, the extension 9 of the pawl is manually elevated which allows each armature to rise and carry its latch bar upward so that the pawl 6 enters recess 29 of the latch bar of each unit.

When the solenoid in any one of the units is energized, the armature 17 on that unit is drawn down, this allows the latch bar in that unit to fall, and in so doing, the rise 30 will rock the pawl 6 to releasing position. If

any other unit is latched, this will release the armature of that circuit and break that circuit before the latch bar engages notch 30 and thus locks that switch 41.

Even though the current through the solenoid ceases, the latched relay will maintain that circuit to transmit any current or any signals that may be sent over the circuit closed by switch 41.

Obviously if the piece 36 was connected to each of the circuits through terminals 46 and 45, the device can be used in the same manner to keep all but one circuit closed and to permit the opening of any one circuit by energizing the relay in that circuit which will close any switch in the other circuits that have been previously opened.

Or, if both terminals 37 and 45 are connected making the switches actuated by arm 41 double throw switches, the device may be used to throw all but the circuit that is being switched from one of the double throw positions to the other.

In the modification shown in Figure 5, the armature 17 of the relay coil 19 is connected to the stem of the valve 50. This valve may be supplied with fluid through a line 51 and may in one position connect the line 51 to line 52 leading to some device and in the other position may cut off the flow into line 52. In the latter position the fluid may be drained out of line 52 to a sump through line 53. It will be understood that valve 50 may be of any other type.

In this modification, if the solenoid 19 in Figure 5 is actuated, it is locked as previously described and the valve 50 is placed in its other position and held there. The act of locking will release, in the manner already described, the armatures 17 connected to the other valves in the other channels.

We claim:

A low-inertia multiple relay, having, in combination, a base plate, a plurality of duplicate units mounted on said base plate, a U-shaped stamping in each of said units, a solenoid mounted on the base of each U-shaped stamping, an armature pivoted on one arm of each stamping having a slot through which a hooked extension on the other arm of the stamping extends to limit the movement of the armature, a second slot in each armature, a guide hole in the base below each of said armature slots, a latch bar which hooks into the second slot in the armature and extends into a guide hole, two notches on each latch bar, a raised portion between said notches, a pawl bar hinged on the base and biased so that the longitudinal edge of the pawl bar enters one of said notches in the latch bar connected to an actuated armature and into the other notch in the latch bars connected to non-actuated armatures, a spring biasing each armature, a contact bar carried by the armature and extending to a point at least as far distant from the armature pivot as the axis of the solenoid but in the opposite direction, a stationary contact engaged by said contact bar when the actuation of the solenoid has moved the latch bar so that the pawl bar enters the proper notch and in the movement of the latch bar the pawl bar has been rocked to release the latch bars of the other armatures.
